[57] CLAIM

The ornamental design for an artificial fireplace log, as shown and described.

DESCRIPTION

FIG. 1 is a front perspective view of an artificial fireplace log, showing my new design;

FIG. 2 is an enlarged left end elevational view thereof, the right end being a mirror image of that shown;

FIG. 3 is a top plan view thereof;

FIG. 4 is a rear elevational view thereof;

FIG. 5 is a front elevational view thereof; and

FIG. 6 is a bottom plan view thereof.

FIG. 1

FIG. 2

FIG. 3

FIG. 4

FIG. 5

FIG. 6
